UNITED STATES PATENT OFFICE.

FRANK H. FRENCH, OF PRESTON, IOWA.

MOP AND BRUSH.

1,110,766.

Specification of Letters Patent. Patented Sept. 15, 1914.

Application filed April 3, 1913. Serial No. 753,709.

To all whom it may concern:

Be it known that I, FRANK H. FRENCH, citizen of the United States, residing at Preston, in the county of Jackson and State of Iowa, have invented certain new and useful Improvements in Mops and Brushes; and I do hereby declare the following to be a full, clear, and exact description of the invention, such as will enable others skilled in the art to which it appertains to make and use the same.

My invention relates to mops or brushes for use in cleaning floors, walls, or windows and more particularly to the class of mops or brushes having oil applied to their fibers so as to render them substantially dustless when in use.

The prime object of my invention is to provide a simple, cheaply constructed and easily manipulated handle fastening which will permit the handle to be used either at a considerable angle to the active edge of the mop, or substantially parallel to the same.

Further objects will be apparent from the accompanying drawings in which:

Figure —1— is a fragmentary elevation of a mop embodying my invention. Fig. —2— is a plan view of the same, with portions of the handle and of the adjoining parts shown in section. Fig. —3— is an enlarged section through the handle of the mop along the line 3—3 of Fig. —1—. Fig. —4— is a fragmentary section through Fig. —2— along the line 4—4. Fig. —5— is a fragmentary view of a floor brush embodying my invention.

In the embodiment of Fig. 1, the mop of my invention consists of a series of fibers 1 strung or looped over a substantially circular metal ring 2, which ring has its ends extending outwardly and prolonged in the form of substantially parallel arms or prongs 3 extending at an angle to the plane of the ring 2. Resting upon the looped portions of the fibers 1 is a disk of felt or other cushioning material 4 having a plurality of perforations through which hook-bolts 5 extend. The said bolts 5 have their hook ends engaged with the ring 2 and their ends threaded to fit nuts 6, by which nuts the bolts may be tightened so as to draw the ring 2 toward the felt disk 4. To stiffen the said disk 4, I preferably position a metal disk 7 above the same, the said disk also having perforations through which the shanks

of the bolts 5 may pass, and having a raised central portion 8 with an opening 9 therein, this opening being normally closed by a swinging cover 10.

When in use, the mop is manipulated by means of a wooden handle 10 having a transverse perforation near one end of the same, through which perforation a bolt 11 extends, the said bolt serving to hold a pair 60 of concavo-convex clamps 12 upon the opposite sides of the handle. Each of the clamp pieces 12 has its concave surface corresponding substantially in curvature to the surface of the handle, and has upon this inner concave surface a recess adapted to receive one of the prongs 3 of the ring member 2 of the mop.

It will be evident from Fig. 3 that when the arms or prongs 3 are inserted in the 75 said recesses between the handle 10 and the respective clamps 12, and the bolt 11 is tightened by means of a thumb-nut 13, the prongs 3 will be firmly clamped between the handle and the clamping members 12, thereby securing the handle to the mop from which the prongs 3 project. The recesses upon the clamps 12 are so disposed that a plane passing through the central line of both recesses (and hence passing through the axis 80 of both arms 3 when the latter are positioned in the said recesses) will not be axial of the handle. Consequently, by loosening the nuts 13 and slipping the handle with its clamps, off the arms 3 and by then rotating 90 the handle so as to bring the respective arms into engagement with the opposite clamps, the angle between the axis of the handle and the active edge of the mop may be altered considerably. Thus, with the angles of the 95 recesses and the angle between the common plane of the prongs and the plane of ring 2 as in Fig. 1, the handle may be changed from its normally inclined position to the substantially horizontal position shown in 100 dotted lines in Fig. 1, thereby permitting the mop to be slid under furniture.

The space between the raised portion 8 of the metal disk 7 and the central portion of the felt disk 4 forms a receptacle into 105 which a suitable oil may be poured by swinging the cover 9 to its open position, whereupon this oil will gradually soak through the felt disk and will be distributed by the disk to the looped portions of the fibers 110 which comprise the brush member of the mop. Consequently, the oil will gradually

soak down along the fibers extending both inwardly and outwardly of the supporting ring 2, instead of being concentrated upon the inner portions of the brush member. 5 Besides acting as a distributor for the oil, the felt disk 4 also acts as a cushioning bumper or guard for the metal reinforcing disk 7 and the nuts 6 above the same, as the protecting edges of the disk 4 (which is larger in diameter than the metal disk 7) form a cushion which will contact with objects of furniture before the edges of the metal disk 7 can impinge against the same. The ring 2 is preferably made of spring metal so as 10 to retain its shape readily when the prongs 3 are slipped out of their normal positions intermediate of the handle and the clamp pieces carried thereby, so that no additional fastening means are required for keeping 15 the main portions of the mop in their normal relations when detached from the handle.

While I have pictured my invention as applied to a cleaning implement having a brush member composed of soft and flexible 20 fibers, it will be evident that it could be embodied equally well in a brush or the like having comparatively rigid or inflexible fibers. Moreover, the interchangeable handle fastening of my invention could be 25 used with various other arrangements of the body member from which the prongs project, such as the brush shown in Fig. 5. To prevent the bolt 11 from rotating relative to the clamps 12 while it is being tightened by 30 the nut 13, I preferably form its shank with a square portion 14 adjacent to the head of the bolt and interfitting a square recess in the adjacent clamp piece. However, I do not wish to be limited to this or other details of the construction herein disclosed, as 35 it is obvious that this might be varied in many ways without departing from the spirit of my invention.

Having more particularly described and 40 claimed the oil-receiving, oil-distributing and cushioning features of my appliance in my copending divisional application, Serial No. 809,536, filed Dec. 30, 1913, I do not herein claim these features of my mop or 45 brush.

I claim as new and desire to cover by Letters Patent:

1. In a brush, a brush member; a pair of prongs mounted thereon; a handle; a 50 pair of inwardly recessed clamp pieces

adapted laterally to engage opposite sides of the handle, and having opposed recesses angularly arranged with respect to the handle in their inner faces to receive the said prongs and engage the same with the handle, 60 and means for forcing the said clamp pieces toward the said handle.

2. In a brush, a brush member; a pair of prongs mounted thereon; a handle; a pair of inwardly recessed clamp pieces adapted 65 laterally to engage opposite sides of the handle, and having opposed angular recesses in their inner faces to receive the said prongs and engage the same with the handle, and means for forcing the said clamp pieces to- 70 ward the said handle; the said prongs and recesses so positioned relative to the cleaning member and the handle respectively, as to change the angle between the handle and the cleaning member upon an interchanging 75 of the prongs adjacent to the respective clamp pieces.

3. In a brush or mop, a ring, the ends thereof extended outwardly to form parallel arms angularly disposed relative to the plane 80 of the ring; a brush member carried by the ring; a handle, a pair of inwardly concave clamps secured to opposite sides thereof, each of said clamps provided on its inner surface with a recess, the said arms positioned in the recesses between the respective clamps and the said handle; the said recesses being angularly disposed with respect to the axis of the handle.

4. In a brush or mop, a ring of spring 90 metal, the ends thereof extending outwardly to form parallel arms angularly disposed relative to the plane of the ring; a brush member carried by the ring; a handle, a pair of inwardly concave clamps secured to 95 opposite sides thereof, each of said clamps provided on its inner surface with a recess, the said arms positioned in the recesses between the respective clamps and the said handle; the said recesses being angularly disposed with respect to the axis of the handle.

In testimony whereof I have signed my name in presence of two subscribing witnesses.

FRANK H. FRENCH.
